Specification for Design.

Patented Feb. 17, 1920.

Application filed April 12, 1919. Serial No. 289,749. Term of patent 14 years.

To all whom it may concern:

Be it known that I, LOUIS A. WEGENAAR, a citizen of the United States, and a resident of the city of New York, borough of Brooklyn, in the county of Kings and State of New York, United States of America, have invented a new, original, and ornamental Design for a Powder-Container or Similar Receptacle.

Reference is to be had to the accompanying drawings in which—

Figure 1 is a side elevation of a container embodying my new design;

Fig. 2 is a plan view.

I claim:

The ornamental design for a powder container or similar receptacle substantially as shown.

LOUIS A. WEGENAAR.
